CLAIM

The ornamental design for a razor handle, as shown and described.

DESCRIPTION

FIG. 1 is a perspective view showing my new design for a razor handle applied to a razor shown in broken lines;

FIG. 2 is a top plan view thereof;

FIG. 3 is a back elevational view thereof;

FIG. 4 is a left side elevational view thereof, the opposite side being a mirror image;

FIG. 5 is a front elevational view thereof, the rear elevation being a mirror image;

FIG. 6 is a bottom plan view thereof;

FIG. 7 is a plan view of a portion of the design identified in FIG. 3 shown separately and on an enlarged scale for clarity of illustration; and,

FIG. 8 is a side view of the portion of the design identified in FIG. 4 shown separately and on an enlarged scale for clarity of illustration.

The broken line showing of the razor is for illustrative purposes only and forms no part of the claimed design.
